United States Patent Office

Des. 175,670
Patented Sept. 27, 1955

175,670

DOORBELL UNIT

Joseph Patrick Corrigan, Leavenworth, Kans.

Application February 28, 1955, Serial No. 34,751

Term of patent 14 years

(Cl. D10—7)

Fig. 1.

Fig. 2.

Fig. 3.

Fig. 1 is a front elevational view of a doorbell unit, showing my new design.

Fig. 2 is a side elevational view thereof; and

Fig. 3 is a top plan view of a doorbell unit.

The opposite side of the doorbell unit is substantially the same in appearance as the side shown.

I claim:

The ornamental design for a doorbell unit, as shown and described.
